UNITED STATES PATENT OFFICE.

THOMAS ROBINSON, OF EVERETT, WASHINGTON.

KEY-RECEPTACLE.

No. 926,963.

Specification of Letters Patent.

Patented July 6, 1909.

Application filed January 17, 1908. Serial No. 411,239.

To all whom it may concern:

Be it known that I, THOMAS ROBINSON, a citizen of the United States, residing at Everett, in the county of Snohomish, State 5 of Washington, have invented new and useful Improvements in Key-Receptacles, of which the following is a specification.

My invention relates to means and methods of recording the condition of mechanisms, 10 and comprises the novel parts, combinations and steps hereinafter described and particularly pointed out in the claims.

The object of my invention is to provide a means and method whereby recording devices such as are now in use may be relied upon to indicate the condition of other mechanisms.

The scope of my invention may be determined by an inspection of the claims terminating this specification.

In the drawings accompanying this specification I have shown my device embodied in a form which is now preferred by me as applied to the recording of the condition of one 25 form of device.

Figure 1 is a sectional elevation of the mechanism employed in connection with a valve. Fig. 2 shows the manner of securing my device in place.

Recording devices, such as the ordinary watchman's clock, which record the time and fact of doing certain acts are in common use. My device is designed for use in connection with devices of this character and to make 30 the record secured a record also of the condition of certain mechanisms at the time the record was made.

A common form of recording device is that known as a watchman's clock, which indicates the performances of a series of acts at 40 various times and places by the actuation thereof through the means of unlike keys distributed along a prescribed route. My device is designed to be attached to, or used 45 in connection with, the controlling member of any suitable mechanism, and to be itself controlled by said member so that the clock-operating or registering key is inaccessible for the operation of the clock, except when 50 this controlling member is in a prescribed position or condition. As such clocks are commonly operated the keys for operating them are accessible at all times and there is no connection between the key and the controlling member which is affected by the posi-

tion of said controlling member, or by the possibility of operating the clock by the key. In other words, the operation of the clock is independent of the position or condition of the device which is supposed to be inspected 60 or guarded by the watchman. As a definite instance of the kind of use referred to may be cited that in connection with the valves of an automatic sprinkler system. In such systems there are often a number of valves 65 by which the presence or absence of water in the pipes may be controlled. In this particular apparatus it is desirable that these valves should be open at all times so that the pipes be filled with water under pressure; 70 otherwise the automatic feature of the system would be destroyed.

By my system and invention I connect the keys at all stations containing mechanisms of this character, with a member of such 75 mechanism which controls its position or condition, or which moves in harmony therewith, and provide means whereby the clock key is made inaccessible for the operation of the clock except when the parts of this mechanism are in the desired position. In the case of a valve the obvious connection would be with the valve stem or with the wheel or lever by which it is operated. A record made by any station key so controlled, is a 80 positive record that the mechanism of that station was at that time in the desired position. The value of such a record in certain contingencies is evident.

My invention is not limited to use with the 90 particular mechanism above mentioned, but it may be applied to the controlling member of any mechanism.

The means which I have chosen to illustrate the application of my invention consist of the valve of a pipe system, such as might be used with a sprinkler system. This mechanism is as follows: The pipe I is supposed to supply water to a sprinkler system and has a valve H therein by which the water 95 is controlled. The stem A, or the wheel B, constitutes the controlling member of this device. A sprocket wheel C is secured to turn with the stem. The chain D passes over this wheel and a companion wheel E. 100 The key K, by which the watchman's clock is operated, is connected with the chain D by a short chain G, and the chain D is inclosed within a casing F, excepting at one end of its course. The casing may be supported in any 105 110

convenient way, as by arm J secured upon the pipe I. When the key is drawn within the casing, as would happen when the valve was closed, it would be impossible for the 5 watchman to operate his clock with this key. His record would, therefore, show a blank for this station, unless he should turn the valve wheel so as to open the valve and thereby make key K accessible. If his record 10 for this station is complete, then it is certain that the valve was open at the time he was there.

The casing F may be of various shapes and dimensions, the essential feature being, only, 15 that it renders the key inaccessible except when the mechanism with which it is used is in the desired position. The connection of the key with the valve stem, or analogous part, may be anything desired so that the 20 key is rendered inaccessible for operation of the clock whenever the valve is closed. There are numerous ways in which this may be done, but further illustration thereof is not deemed necessary.

25 It is evident that my invention may be applied to the checking and recording of the condition of any type of controlling member for any kind of mechanism. The means which may be employed for connecting the 30 clock keys with said controlling members, is capable of wide variations without departing from the spirit of my invention.

The essence of my invention lies in the connection of the member by which the recording 35 device is operated with a member by which another device is controlled, so that said operating member is inaccessible for the operation of the recording device except when the controlling member is in a certain 40 position or positions. This position in the case of a valve may be either open or closed as desired.

My invention may be employed in connection with the recording of the condition 45 of valves, doors, locks, and other movable devices which control various conditions and mechanisms.

The mechanism as to which it is desired to provide a record, which mechanism as herein 50 shown and described consists of the valve H, may, for convenience be called the primary mechanism, while the time clock or analogous mechanism may be called a secondary mechanism. The terms "time clock" 55 and "key", wherever used are to be construed as generic terms meaning—the former any recording mechanism suitable for such uses; and the latter, any device used for operating the former to produce a record.

60 Having thus described my invention, what I claim as new and desire to secure by Letters Patent is:

1. A means for checking the indications made by a recording device, such as a time 65 clock, when used to record the condition of

a movable primary mechanism, comprising a key for operating the recording device, a controlling member by its relative position determining the usability of the key, and means permanently connecting the key with the 70 primary movable mechanism to produce relative movement between the two, whereby the usability of the key is determined.

2. The combination with a movable apparatus as to the condition of which a record 75 is desired, of a member adapted to be employed as a key or operating member for a recording device, means permanently connecting said key with a movable part of the first named apparatus, and means whereby 80 the movement of the key thus caused determines its usability.

3. The combination with a movable member of an apparatus as to which a condition record is desired, of a key or analogous member 85 adapted to operate a recording device, a permanent connection between said parts whereby said key is moved in correspondence to said movable member, and a shield rendering said key unusable in certain positions of 90 the key.

4. The combination with a member of an apparatus as to the condition of which a record is desired, said member being rotatable and by its rotation controlling the condition of said apparatus, a sprocket chain running upon said member, a companion or idler wheel for said chain, a key carried by said chain and adapted to operate a recording device, and a shield covering said key in certain 100 positions thereof.

5. A recording or check attachment for movable controlling parts of mechanisms, comprising a key adapted to operate a recording device, a casing and means connecting 105 said controlling part with the key to draw the key within the casing in certain positions of the controlling part.

6. In a sprinkler system, the combination of a valve, a sprocket chain movable with and 110 by said valve and carrying a key, and a shield adapted to cover said key in certain positions to thereby render it inaccessible for operating a recording device.

7. In a sprinkler system, the combination 115 with a valve thereof, a key adapted to operate a recording device, a shield for said key, a movable member of said valve which controls its opening, and permanent connections between said key and said member, whereby 120 when the valve is in a predetermined position said shield renders the key unusable.

8. In a sprinkler system, in combination, a valve, a rotatable stem for said valve, a wheel turned by said stem a chain moved by 125 said wheel, a key secured to said chain and adapted to operate a recording device, and a shield covering said key and rendering it unusable in certain positions of the valve.

9. In a sprinkler, in combination, a valve, 130

mechanism for opening and closing said valve, a key, mechanism permanently connecting said key with the valve opening and closing mechanism whereby the position of the key is determined, and a shield adapted to cover said key in certain positions of the valve operating mechanism and to thereby prevent the operation of a recording device by said key.

THOMAS ROBINSON.
